United States Patent

Des. 238,251

Patented Dec. 30, 1975

238,251

JEWELRY DISPLAY SUPPORT OR SIMILAR ARTICLE

Iraida Garey, New York, N.Y., assignor to
D. Lisner & Co., Inc.

Filed Jan. 2, 1974, Ser. No. 430,225

Term of patent 14 years

Int. Cl. D9—99

U.S. Cl. D9—191

FIG. 1

FIG. 2

FIG. 3

FIG. 4

FIG. 5

FIG. 1 is a front elevational view of a jewelry display support or similar article, showing my new design;

FIG. 2 is a side elevational view thereof;

FIG. 3 is a top plan view thereof;

FIG. 4 is a rear elevational view thereof; and

FIG. 5 is a bottom plan view.

I claim:

The ornamental design for a jewelry display support or similar article, as shown.
